UNITED STATES PATENT OFFICE.

RUSSELL D. A. THOMPSON, OF BEAVER, PENNSYLVANIA, ASSIGNOR TO GILL BROTHERS COMPANY, OF STEUBENVILLE, OHIO, A CORPORATION OF WEST VIRGINIA.

DESIGN FOR A SHADE-BOWL.

42,927.

Specification for Design.

Patented Aug. 20, 1912.

Application filed June 7, 1912. Serial No. 702,349. Term of patent 7 years.

To all whom it may concern.

Be it known that I, RUSSELL D. A. THOMPSON, a citizen of the United States of America, and a resident of Beaver, county of Beaver, State of Pennsylvania, have invented a certain new, original, and ornamental Design for a Shade-Bowl, of which the following is a specification.

The drawing is an elevation of the shade in upright position.

The shade consists of a bowl having its side and bottom portion formed in a plurality of lobes or breasts separated by orn-

mented areas 2, the bowl also having a flaring periphery 3 with an ornamental border 4, the whole being of a Louis XV design.

I claim:

The ornamental design for a shade bowl as herein described and shown.

Signed by me at Beaver, Pennsylvania, this 28th day of May, 1912.

RUSSELL D. A. THOMPSON.
